By his Attorney:
John E. Earle.

United States Patent Office.

CHARLES B. BRISTOL, OF NEW HAVEN, CONNECTICUT.

Letters Patent No. 83,757, dated November 3, 1868.

IMPROVED CURRY-COMB.

The Schedule referred to in these Letters Patent and making part of the same.

To all whom it may concern:

Be it known that I, CHARLES B. BRISTOL, of New Haven, in the county of New Haven, and State of Connecticut, have invented a new Improvement in Curry-Combs; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view of the comb complete; Figure 2, a central section; and in

Figure 3, a top view of the shank and comb.

This invention relates to an improvement in the article of manufacture known to the trade as "curry-combs," the object being to produce a simple, cheap, and durable comb; and the invention consists in constructing the shank and teeth upon one and the same bar, from cast-metal, and combined with a wrought-metal plate, secured to the said bar, the two edges of which turn down, and cut so as to form fine teeth upon the said two edges, as in the common curry-comb.

In order to the clear understanding of my invention, I will fully describe the same as illustrated in the accompanying drawings.

A is the handle, B, the shank, which is formed upon a bar, C, as seen in fig. 3, the said bar provided with comb-teeth, *a*, more or less in number, all cast together in one and the same piece. And to the said bar I attach a wrought-metal plate, D, by means of rivets through the bar, as at *d*, fig. 1.

The two edges, E, of the plate D are turned down, and cut into fine teeth, as denoted in fig. 1.

This completes the construction, and I have produced a curry-comb, at very little expense, equally durable, and practically as good as the larger and more expensive combs.

Having fully described my invention, What I claim as new and useful, and desire to secure by Letters Patent, is—

As an article of manufacture, a curry-comb, in which the bar C, teeth *a*, and shank B, are formed in one and the same piece, and united to the plate D, the whole constructed substantially in the manner herein set forth.

CHAS. B. BRISTOL.
